(57) **CLAIM**

The ornamental design for a tamper cup seal, as shown and described.

DESCRIPTION

FIG. 1 is a perspective view of an assembled tamper cup seal showing my new design;

FIG. 2 is a side view thereof;

FIG. 3 is a top view thereof;

FIG. 4 is a bottom view thereof;

FIG. 5 is a cross section view taken along line 5—5 of FIG. 4;

FIG. 6 is a perspective view of a disassembled tamper cup seal;

FIG. 7 is a side view of a disassembled tamper cup seal shown for ease of illustration; and,

FIG. 8 is a cross section of a disassembled tamper cup seal shown for ease of illustration and taken along line 8—8 of FIG. 7.

The claimed cup seal is used to cover and protect a screw from being removed, can be countersunk flush to protect the cup seal, and shows evidence of tampering.

1 Claim, 8 Drawing Sheets
